COSMETIC CASE

Martin M. Slaton, Burbank, and Mack M. Croen, Los Angeles, Calif.

Application March 26, 1945, Serial No. 584,778

2 Claims. (Cl. 132—79)

This invention relates to cosmetic cases and particularly one of the type frequently designated as compacts, which is designed to incorporate not only the customary lipstick and powder, but also a small vial of perfume.

One of the features which contributes to the success of a compact is its very compactness so that it can be readily carried about in a purse or bag. Particularly when women attend formal affairs, they are accustomed to carry very small purses and on such occasions frequently find it desirable to carry along not only lipstick and powder but a small quantity of perfume also. For the most part, these items are carried separately, inasmuch as they are sold separately in stores. That is to say, there will be a separate container for lipstick, another for powder and rouge and if perfume is carried, a separate vial of perfume. When the items are used a cover must be removed from each one, so that when a lady sits down to make her toilet she has a great many separate articles scattered about the table.

For convenience in carrying these various articles, it is therefore among the objects of the invention to provide a new and improved three-chamber container wherein one container may form the cap for the container in the second chamber and wherein all are joined together in a neat and convenient package which can be readily carried about in a purse.

Another object of the invention is to provide a new and improved container having several chambers wherein the different parts are so compactly positioned one above the other and so joined by pivotal means that any one chamber may be opened without it being necessary to open any of the other chambers.

Still another object of the invention is to provide a new and improved multiple chamber compact which takes advantage of the resiliency of the material of which it is composed together with a special type of resilient hinge so that in spite of frequent openings and closings, the parts will always be capable of being retained snugly together so that the contents are properly held in place.

With these and other objects in view, the invention consists in the construction, arrangement and combination of the various parts of the device whereby the objects contemplated are attained, as hereinafter more fully set forth, pointed out in the claims and illustrated in the accompanying drawing, in which:

Fig. 1 is a side elevational view of the device.

Fig. 2 is a longitudinal sectional view showing the various parts of the device in closed position.

Fig. 3 is a bottom view of the device.

Fig. 4 is a cross-sectional view of the device taken on the line IV—IV of Fig. 2.

Fig. 5 is a detailed view of the washer providing a spring for the pivotal means.

In the past it has been the practice to make compacts relatively flat so that they could be conveniently carried in a pocket book or purse or in the pocket of the user. The compacts previously used are relatively large in diameter, presumably in order that a sufficiently large powder puff could be used. Where attempts have been made to include in compacts of this general description additional cosmetic articles, such as rouge and mascara, it has been necessary to make them so thick that they are inconvenient and undesirable. Moreover, when the thickness is increased, it is always necessary either to provide relatively sharp corners or to so increase the size in order to round the corners that the size becomes prohibitive. If the size of a device of this kind is increased, the problem of keeping the cover closed becomes greater, since a large cover is much more difficult to hold tightly closed than a small cover. Then, too, the means for holding the cover tightly closed should not be so cumbersome and difficult to manipulate that the cover cannot be quickly opened whenever desired. In order, therefore, to provide suitable accommodation for more than the customary powder in compacts some change of design becomes advisable.

In order, therefore, to provide a multiple chambered cosmetic receptacle, there is shown in the embodiment of the invention chosen for the purpose of illustration, a substantially cylindrically shaped compound case 10 which has a lower portion 11, an upper portion 12 and a lid 13. In the lower portion is chamber 14 which opens downwardly and which has a threaded end 15 into which may be inserted a correspondingly threaded section 16 of a lipstick holder 17, the outer portion of which overlies the bottom end of the case and forms a closure for the chamber 14. The lipstick holder may be provided with the customary stick type of lip rouge 18.

Immediately above the lower chamber is an intermediate chamber 19 separated from the lower chamber by a partition 20. The intermediate chamber is adapted to receive a small perfume vial 21 which may be seated in a resilient ring 22 so that it will not accidentally fall out of place.

The upper portion 12 contains a chamber 23 which is designed to contain a quantity of powder 24 and a powder puff 25 which is designed to have substantial thickness and be compressed within the diameter of the chamber so that it may spread when the powder is applied. The upper portion 12 has a bottom 26 which, when the case is entirely closed, forms a closure for the chamber 19. In order to retain the upper portion in position over the lower portion, there is provided a protuberance 27 of the material of which the device is made which is designed to seat within a recess 28 in top face of the lower portion.

Similarly a protuberance 29 is provided on the lower face of the lid designed to be received in the recess 30 of the upper face of the upper portion 12.

In order to hold all of the parts in position, the upper and lower portions together with the lid are provided respectively with rearward extending protuberances 31, 32 and 33 which are identical in cross sectional shape and positioned one above the other. A central bore 34 of uniform diameter extends through all of the protuberances and positioned within the bore is a shaft or pin 35. The pin is anchored at its upper end 36 by insertion into an insert 37 as by threading, the insert having been preferably moulded into the lid. The shaft is designed so as to be permanently attached to the lid once the device is assembled.

At its lower end the shaft is threaded to receive a nut 38 which fits within an enlargement 39 at the end of the bore 34 forming a shoulder 40. Seated upon the shoulder is a dished, resilient washer 41 which is pressed into place by application of the nut 38 to the threaded end of the shaft. The washer may be of inherently resilient material or may be slotted so that it will have a spring effect. When the nut has been tightened into place upon the shaft, it will draw all of the parts of the case tightly together. By reason, however, of the interposition of the resilient spring washer 41, it will be possible to separate the various parts a slight amount. This separation will permit the protuberance 29, for example, to be lifted from its recess 30 so that the lid can be rotated upon the shaft 35 in order to open the powder chamber 23. Similarly, the upper portion 12 may be lifted a slight amount so that the protuberance 27 may be removed from its recess and permit rotation of the upper portion 12 about the shaft in order to open the perfume chamber 19. Chambers 12 and 19 may thus be simultaneously opened or may be opened one at a time, depending upon the desire of the user.

To remove the lipstick, it is necessary only to unscrew the lipstick holder from the bottom chamber. It will be noted that when the lipstick holder is in place, the outer rim of the holder will partially cover the enlargement 39 so as to conceal the nut 38.

There has therefore been provided a compact cosmetic holder having a plurality of chambers which may be opened together or individually 10 and which may be moulded, as for example, of some plastic material or formed otherwise from material such as wood or metal to a convenient size and shape in order that it may be readily carried about in a purse and so that the several parts can be used without it being necessary to separate any one part from the rest.

We claim:

1. A combination multiple service compact including a plurality of respectively moving parts comprising an elongated, rounded container having a lower and an upper chamber therein, a cosmetic carrying cap engaging the outer end of one of said chambers, a second rounded container having a chamber therein in axial alignment with the first forming a cap for the other of said chambers in the first container, a cover for the chamber in the second container, detent means respectively between the cover and the second container and between the second and 20 first containers comprising interengaging elements on the adjoining surfaces and a connecting shaft extending through the edges of the containers and cover comprising a pivot about which said parts respectively rotate one with relation to the other.

2. A combination multiple service compact including a plurality of respectively moving parts comprising a substantially cylindrical container having a lower and an upper chamber therein and a dividing partition, a hollow lipstick carrying cap threadably engaging the outer end of one of said chambers, a second smaller cylindrical container having a chamber therein in axial alignment with the first forming a cap for the other of said chambers in the first container, a cover for the chamber in the second container, detent means respectively between the cover and the second container and between the second and first container comprising a protuberance on one contacting surface and a co-operating receiving recess in the other and a connecting shaft extending through the edges of said containers and the cover comprising a pivot about which said parts rotate respectively 30 one with relation to the other.
